UNITED STATES PATENT OFFICE.

JOHN N. DAVIS, OF DAYTON, OHIO, ASSIGNOR TO THE WESTON PAPER AND MANUFACTURING COMPANY, OF DAYTON, OHIO, A CORPORATION OF OHIO.

PAPER PAIL.

SPECIFICATION forming part of Letters Patent No. 692,990, dated February 11, 1902.

Application filed September 18, 1899. Serial No. 730,861. (No model.)

To all whom it may concern:

Be it known that I, JOHN N. DAVIS, a citizen of the United States, residing at Dayton, county of Montgomery, and State of Ohio, whose post-office address is Dayton, Ohio, have invented a certain new and useful Improvement in Paper Pails, of which the following is a full, clear, and exact description, reference being had to the accompanying drawings, forming part of this specification.

My invention relates to oyster-pails designed for liquids, oysters, berries, ice-cream, and the like.

The special object of the invention is to form a very close and tight-fitting top for the pail to prevent the contents from leaking or spilling out, being a certain novel construction and arrangement of parts to be herein-after particularly pointed out and claimed.

In the drawings, Figure 1 is a perspective view of the pail closed up as in use. Fig. 2 is a detail cross-section on the lines 2 2 of Fig. 1, showing the method of attaching the bail. Fig. 3 is a perspective view of the pail open to receive the contents. Fig. 4 is a plan view of the blank from which the pail is formed.

The pails are cut and scored from sheets of suitable paper to form the blanks, as shown in Fig. 4, the score-lines *a b c d* forming the bottom *A*, and the score-lines *e, f, g, h, i, j, k, l* forming the sides *B B* and ends *C C*. The corner folds between the sides and ends are formed by the score-lines *o, p, q, r*. The side flaps *D* and *E*, forming the inside top cover, are folded on the score-lines *m m*, each of which side flaps are provided with tucks *F G* and *H I*, which tucks are pushed in along the end walls when the box is folded, as will be herein-after described, while *K L* are the end flaps folded on score-lines *s t* to form the outside top cover, locked by a tin clasp.

In folding the pail the end walls and side walls are brought up into upright position, and the corner folds between these walls are folded on the score-lines *o p q r* to form the

side flaps *M N*. The wire bail *P* is then secured to the openings *u* in the corner fold, and the side tucks *F, G, H*, and *I* being bent 50 inward and the strip of tin *R* being secured in one of the openings *w* in the end flap *K* the package is in the shape shown in Fig. 3, ready for nesting for transportation and when separated for the receipt of the oysters or 55 what not. The side flaps *E D* are then pressed down, one over the other, to form the cover for the contents, and the side tucks *F, G, H*, and *I* being pushed down along the end walls *C C*, thus completely and tightly closing the 60 top. These side tucks are also made full large, so as to render a close tight fit all the way around. The end flaps *K* and *L* are then brought over, and the end of the tin strip *R* is passed through the opening *y* in the flap *L* 65 and then bent down flat with the top, securely locking the package.

It will be seen from my construction, as above described, that the ends of the bail do not pierce any portion of the inner walls of 70 the pail and that therefore there is no liability of leakage and no opportunity for the scratching or destroying of any of the pails when they are nested. The side flaps *E* and *D* being of the full width of the top and being provided with the side tucks *F, G, H*, and *I*, when these parts are folded down, as described, every opening of the pail is securely covered, so that there is no opportunity whatever for spilling the contents. The tin clasp 80 secured to one of the ends and locked through the opening in the other end flap then forms a very convenient and close-fitting top cover and lock for same.

Having thus described my invention, what 85 I claim, and desire to secure by Letters Patent, is—

A pail made from a single blank of paper scored and creased to form bottom, sides and ends, with uncut corner folds between the 90 sides and ends to fold together to form side laps, and having side and end flaps attached to the sides and ends, each of the side flaps being of a size to completely cover the top

and carrying side tucks the full length of the side flaps to fold down along the ends when the pail is closed, and the end flaps disconnected from the side flaps provided with a 5 clasp to fasten same together over the side flaps, and a bail attached to the adjacent side laps but not piercing the side walls of the

package, substantially as shown and described.

JOHN N. DAVIS.
